UNITED STATES PATENT OFFICE

2,453,443

SELF-SERVING TABLE

Evelyn Logan, Washington, D. C.

Application August 21, 1946, Serial No. 691,996

1 Claim. (Cl. 311—33)

1

This invention relates to tables, and more particularly to self-serving tables.

An object of this invention is to provide a table having a revolving center upon which food is placed, and upon rotation of the center, the food can be presented to each guest in succession as desired.

Another object of the invention is to provide a removable tray that mounted on the center can be revolved therewith, the tray being filled with food prior to the placing thereof on the table.

With the above and other objects and advantages in view, the invention consists of the novel details of construction, arrangement and combination of parts more fully hereinafter described, claimed and illustrated in the accompanying drawings in which:

Figure 1 is a top plan view of an embodiment of the invention;

Figure 2 is an elevational view thereof;

Figure 3 is a sectional view on the line 3—3 of Figure 1;

Figure 4 is a sectional view showing the tray which is removable from the table;

Figure 5 is a side view of a caster wheel;

Figure 6 is a top view thereof and

Figure 7 is an end view thereof.

Referring more in detail to the drawings, the reference numeral 10 designates a table pedestal, to the upper end of which is secured a circular table top 11.

Secured to the top in vertical relation therewith, and relatively spaced from each other adjacent the periphery of the top on the upper side thereof, are the pegs or dowels 12, on which are mounted the spacing members 13.

Positioned on the members 13 and connected to the pegs 12 is the ring member 14 of a size to conform to the top 11, and spaced therefrom to provide the open space 15 to receive soiled dishes or the like.

Secured to the under-side of the ring member 14 so that they extend beyond the inner periphery of the central opening 16 in the ring, are the brackets 17 in which are journaled the pin axles 18 for the flanged caster wheels 19.

Mounted for rotation on the wheels 19 is the circular member 20, and the periphery of this member engages the flanges on the wheels 19 to retain the member 20 thereon.

At the center of the member 20 there is secured in vertical relation therewith, the peg 21, and at the periphery of the member 20 in radial alignment with the peg 21 are secured a plurality of vertical pegs 22.

Removably mounted on the member 20 is the tray 23 which is of the same size as the member

20, and is provided with apertures 24 to receive the pegs 22 thereof. Therefore, while the tray can be removed from the member 20, it will be forced to rotate with this member by means of the pegs 21 and 22.

Handles 25 secured to the upper side of the tray adjacent the periphery thereof permit carrying of the tray, and also permit the tray and member 20 to be rotated thereby.

10 In use, the tray is filled with food in the kitchen, and is then brought and placed upon the member 20. The dishes for the guests are placed on the ring 14, and the tray is rotated to serve the guests as desired. The soiled dishes are removed 15 from the ring to be placed in the space therebelow.

It is believed that the construction and operation of the invention will be apparent to those skilled in the art, and it is to be understood that 20 changes in the minor details of construction, arrangement and combination of parts may be resorted to, providing they fall within the spirit of the invention, and the scope of the appended claim.

25 Having thus described the invention, what is claimed as new and desired to be secured by Letters Patent is:

A device of the character described, comprising a table top, a pedestal secured thereto, vertically 30 disposed pegs on said top spacing members on said pegs for supporting a ring in spaced relation thereto, a bracket secured to and extending beyond the periphery of the inner opening of said ring, a pin carried by said bracket to support revolving means thereon, a circular member mounted on said revolving means, a tray mounted on said circular member and vertically disposed pegs 35 on said member for coaction with openings in said tray for detachably mounting said tray on said circular member.

EVELYN LOGAN.
